UNITED STATES PATENT OFFICE.

GEORGE E. RICHMOND, OF AUSTIN, TEXAS.

AIRSHIP.

1,270,971.

Specification of Letters Patent. Patented July 2, 1918.

Application filed June 8, 1917. Serial No. 173,198.

To all whom it may concern:

Be it known that I, GEORGE E. RICHMOND, a citizen of the United States, residing at Austin, in the county of Travis and State of Texas, have invented new and useful Improvements in Airships, of which the following is a specification.

This invention relates to improvements in airships of the lighter-than-air type, where-
10 in the body or car of the craft is supported by one or more gas fields or aerostats, each constructed of an outer inclosing casing or envelop containing a multiplicity of small balloons or gas bags therein, so that in case
15 of rupture of one or more of the bags and the escape of gas therefrom the buoyancy of the remaining bags will remain unimpaired.

One object of the present invention is to
20 provide an airship which is adapted to be readily and conveniently handled and to support one or more persons besides the pilot or aeronaut, and which may be caused to ascend or descend in a straight path, hover over any given point, and alight upon and rise from the surface of a body of water.

A further object of the invention is to
30 provide an airship having aerostats arranged on opposite sides of the longitudinal center thereof and centrally supporting a car suspended therefrom, each of which aerostats comprises an envelop adapted to serve as a parachute in the event of danger and to protect the inclosed gas bags in an
35 effective manner.

A further object of the invention is to
40 provide an aerostat including an envelop adapted for the free circulation of air therethrough, and small captive balloons ar-
45 ranged within the envelop and connected with restraining cords so as to have a limited range of movement, whereby in the event of the penetration of the shell by a missile liability of damage to the inclosed balloons will be reduced to the minimum, the balloons also being kept cool by the air circulating through the envelop to obviate liability of undue expansion thereof.

A still further object of the invention is
50 to provide a means for automatically quenching any fire which may start to break out within the aerostat, so as to diminish liability of the explosion thereof.

A still further object of the invention is
55 to provide a propelling system including a main engine for operating the driving pro-

peller, one or more lifting propellers, an electric circuit including a motor and storage battery for driving said lifting propellers, a generator on the main engine shaft 60 for replenishing the batteries, and means whereby the generator may be made to serve as a motor driven by current from the battery in the event of stoppage of the main motor. 65

A still further object of the invention is to provide an airship which is simple of construction and may be built and operated at a comparatively low cost.

With these and other objects in view, the invention consists of the features of construction, combination and arrangement of parts hereinafter fully described and claimed, reference being had to the accompanying drawings in which: 75

Figure 1 is a front elevation of an airship embodying my invention.

Fig. 2 is a side elevation of the same.

Fig. 3 is a top plan view of the airship.

Fig. 4 is a vertical transverse section 80 thereof on the line 4—4 of Fig. 2.

Fig. 5 is a vertical longitudinal section through one of the aerostats.

Fig. 6 is a horizontal section through the car near the top thereof. 85

Fig. 7 is a fragmentary perspective view of the envelop of one of the aerostats.

Fig. 8 is a detail view of the rudders.

Fig. 9 is a diagrammatic view of the electric circuit and connections. 90

Referring now more particularly to the drawings, 1 designates a car constructed of any suitable light and durable material, and which is adapted for transit through the air, as well as to readily light and float upon 95 the surface of a body of water. This car is designed to house the pilot or aeronaut and an assistant or one or more passengers, the fuel, provisions and other impedimenta to be carried, and the engines and other in- 100 closed working parts of the ship. The general shape or form of the car is that disclosed, but any other suitable shape or form of car may be employed.

Disposed at a suitable elevation above the 105 top of the car is a frame structure 2 with which the car is connected by suitable suspending connections 3, and disposed upon opposite sides of said frame structure 2 and suitably secured thereto, are aerostats 4, 110 which are also suitably secured at their keel or base portions to brackets or outriggers 5.

fixed to and extending outwardly from the sides of the car.

These aerostats 4 are designed to have sufficient lifting capacity to approximately 5 sustain the weight of the car and the load carried thereby, thus diminishing the amount of power required for ascension and propulsion, and each aerostat is fish-shaped or of other suitable stream-line form and comprises an outer casing or envelop 6 containing a mass or multitude of gas bags 7.

The casing 6 of each aerostat is made of some strong but light and durable metal, and is formed of segmental sections 6', the 15 meeting edges of which are provided with flanges 8, the flanges of adjacent sections being united by bolts or rivets 9. The upper, substantially dome-shaped half of each envelop is imperforate, while the lower semi-20 elliptical half of the envelop is perforate throughout for the admission of air, whereby in the event of the fall of the craft, from accident or other cause, air will enter the aerostat casings through the lower perforate portions thereof and bank or be compressed within the upper imperforate portions thereof, whereby the aerostats are adapted to serve as parachutes to diminish the speed of descent and allow a safe landing 25 30 to be made. At the front of each aerostat is a central air intake opening 6^a, and at the rear of each aerostat is an air outlet or discharge opening 6^b, whereby in the forward travel of the ship air will be allowed to pass 35 longitudinally through the envelop, for circulation through and between the gas bags, 7, whereby said bags will be kept cool and prevented from becoming overheated and expanding to an undue extent. The openings 6^a and 6^b also serve as vents to permit 40 of the escape of air from the envelop when performing the function of a parachute.

The gas bags 7 are made of rubber or other suitable material, containing hydrogen or 45 other buoyant gas, each bag being of cylindrical or other suitable form. The bags are nested within the envelop and permitted to have a relative shifting motion to a determined degree, and to this end are attached 50 to the upper ends of confining or tethering cords 10, which are suitably fastened at their lower ends to the keel of the envelop. By this construction and arrangement of the gas bag, spaces are provided between the 55 bags for the flow of cooling currents of air, while the usual factor of safety is obtained in confining the body of buoyant gas within a plurality of separate and individual bags instead of within a single bag or receptacle. 60 Each bag is also backed by a resilient mass of other bags, so that in the event of the penetration of the envelop by a missile any bags struck, unless solidly hit, will yield and allow the missile to pass through the envelop 65 without perforating any bag, while in the

event of the perforation of any particular bag its resilient or cushioning action will tend to prevent destruction of other bags, thus securing a greater range of safety. The described arrangement of the bags also provides for the compression of the inclosed air for a parachutic action as previously explained, as will be readily understood. For the purpose of providing for the extinguishment of any fires which may start within the 70 aerostat, I provide at the top of each aerostat a tank or other water receptacle 11 having a filling opening normally closed by a plug or other suitable closure 12. A pipe 13 leads from this tank downwardly to a 80 sprayer head 14 arranged within the upper portion of the aerostat, and which sprayer head is provided with suitably arranged nozzles, each closed by a closure device of any suitable construction which will be 85 opened when the temperature within the envelop rises above a normal predetermined temperature, so that in the event of the starting of a fire the interior of the envelop will at once be flooded with water from the 90 tank. By this means the fire will be extinguished before it can spread to any extent or cause an explosion, the water draining out through the perforated bottom of the envelop to restore normal conditions within 95 the aerostat upon the extinguishment of the flame.

The propelling mechanism of the craft comprises a forward tractor or driving propeller 15 mounted upon a shaft 16 and driven 100 from a main engine 17 preferably of the internal combustion type, said engine being supplied with gasoline or other fuel from a storage tank 18 contained within the body 1. In addition to the propeller 15 one or 105 more, preferably two, lifting propellers 19 are employed, said propellers being mounted upon vertical shafts 20 adapted to be driven by friction gearing 21 from a transmission shaft 22 suitably driven from an electric motor 23. The friction gearing may be of a well known type which may be manually thrown into and out of action at will and the gears of which are relatively adjustable to vary their speed, so that the lifting propellers 110 may be thrown into and out of action as desired and their speed of action governed to assist in sustaining the machine in flight, or adapt it to rise to any desired elevation 115 at the will of the pilot. The motor 23 is supplied with current from storage batteries 24, which are constantly replenished with current in the travel of the machine from a generator 25 on the shaft 16, the feed conductors between said batteries and generator 120 being arranged so as to be governed by a pole reversing switch 26, which in one position will connect the elements for the transmission of current generated by the generator 125 to the batteries, which in another posi- 130

tion will reverse the direction of the current for flow from the batteries to the field of the generator. Thus in the event of the stoppage or derangement of the main motor 17 current from the storage batteries may be supplied to the generator, which through its reversal of action will operate as an electric motor, thus driving the shaft 16 so that a continuity of flight may be maintained.

10 The ship is designed to be steered and stabilized by means of a tail piece forming a laterally swinging vertical rudder 27 and vertically swinging horizontal rudder 28, which rudders are coupled by connections 27' and 28' to concentrically mounted control wheels 29 and 30 arranged within the car in suitable proximity to the pilot's seat 31, whereby said rudders may be conveniently operated for steering and stabilizing 15 actions. Springs 31' are provided for automatically maintaining the rudders in normal position, and resisting deflection thereof from such position, so that when strong or adverse currents of air are encountered accidental adjustment of the rudders under the pressure thereof will be prevented or resisted until the pilot can regain control. The car is also designed to be equipped with a suitable seat for the pilot's assistant, an 20 observer or a passenger, and may be furnished with suitable look-out or observation ports constructed and arranged in any suitable manner.

From the foregoing description, taken in 35 connection with the drawings, it will be seen that my invention provides an airship of the character set forth which is simple of construction and designed to carry out the objects of the invention in a reliable and 40 efficient manner. It will, of course, be understood that while the construction disclosed is preferred, changes falling within the scope of the appended claims may be made without departing from the spirit or 45 sacrificing any of the advantages of the invention.

I claim:

1. In an airship, a driving propeller, a lifting propeller, a main motor for actuating 50 the driving propeller, an electric motor for actuating the lifting propeller, a storage battery for supplying current to said electric

motor, a generator driven in the operation of the propeller by the main motor for furnishing current to replenish the battery, and 55 means for reversing the flow of the current for supplying current from the battery to the generator so as to convert said generator into a motor for driving the propeller in the event of the stoppage or derangement 60 of the main motor.

2. In an airship, an aerostat comprising an envelop having an upper imperforate portion and a lower perforate portion, and 65 a plurality of separate and independent gas bags disposed in spaced relation within the aerostat.

3. In an airship, an aerostat comprising an envelop having an upper imperforate portion and a lower perforate portion, and 70 provided with fore-and-aft air inlet and air discharge openings, and a plurality of separate and independent balloons arranged in spaced relation within said envelop.

4. In an airship, an aerostat comprising 75 an envelop having an upper imperforate portion and a lower perforate portion and provided with fore-and-aft air intake and discharge openings, a series of separate and independent gas bags arranged within said 80 aerostat, and tethering cords connected with the respective balloons at their upper ends and with the bottom portion of the envelop at their lower ends and flexibly maintaining 85 said gas bags in position.

5. In an aerostat, an envelop comprising a body of sheet metal made up of assembled sections, said envelop having an imperforate upper portion and a perforate lower portion, and provided with fore-and-aft intake and 90 discharge openings at about the medial longitudinal line thereof, and a plurality of separate and independent captive balloons arranged in massed formation within said 95 envelop.

6. In an aerostat, an envelop, gas bag within the envelop, a receptacle for an extinguishing fluid mounted upon the top of the envelop, and means controlled by the internal temperature of the envelop, for supplying the extinguishing fluid to the interior 100 of said envelop.

In testimony whereof I affix my signature.
GEORGE E. RICHMOND.
